(57) **CLAIM**

The ornamental design for apparatus for medical tests, as shown and described.

DESCRIPTION

FIG. 1.1 is a left side view of a first embodiment of an apparatus for medical tests;

FIG. 1.2 is a perspective view thereof;

FIG. 1.3 is another perspective view thereof;

FIG. 1.4 is a front view thereof;

FIG. 1.5 is a right side view thereof;

FIG. 1.6 is a back view thereof;

FIG. 1.7 is a bottom view thereof;

FIG. 1.8 is a top view thereof;

FIG. 6.1 is a left side view of a second embodiment of an apparatus for medical test;

FIG. 6.2 is a perspective view thereof;

FIG. 6.3 is another perspective view thereof;

FIG. 6.4 is a front view thereof;

FIG. 6.5 is a right side view thereof;

FIG. 6.6 is a back view thereof;

FIG. 6.7 is a bottom view thereof; and

FIG. 6.8 is a top view thereof.

The broken lines shown in FIGS. 1.2, 1.3, 1.4, 1.6, 1.7, 6.2, 6.3, 6.4, 6.6, and 6.7 illustrate portions of the apparatus for medical tests that form no part of the claimed design.
